UNITED STATES PATENT OFFICE.

JAMES HARVEY STRONG, OF STEUBENVILLE, OHIO.

DESIGN FOR A SHADE-BOWL.

45,030.

Specification for Design.

Patented Dec. 9, 1913.

Application filed October 15, 1913. Serial No. 795,372. Term of patent 7 years.

To all whom it may concern:

Be it known that I, JAMES HARVEY STRONG, a citizen of the United States of America, and a resident of Steubenville, county of Jefferson, State of Ohio, have invented a certain new, original, and ornamental Design for a Shade-Bowl, of which the following is a specification.

Referring to the drawing, Figure 1 is a view half in elevation and half in vertical central section showing the bowl in upright position. Fig. 2 is a bottom plan of the same.

The shade consists of a bowl 1 having its surface formed in a plurality of tapering flutes 2 radiating from the lower pole 3, the flutes being shaped in the form of an

acute triangle, as seen in plan in Fig. 2, having their vertices 4 adjacent the pole and their bases 5 disposed upward toward the equator or periphery 6. Superimposed on each flute is a raised flute 7, similar in outline but of lesser longitudinal and lateral dimension. The flutes have their vertices overlying those of the first named flutes.

I claim:

The ornamental design for a shade bowl substantially as shown and described.

Signed by me at Steubenville in the State of Ohio this 25th day of September, 1913.

JAMES HARVEY STRONG.
